UNITED STATES PATENT OFFICE

149,502

DESIGN FOR A TRICYCLE

Rudolph Kartarik, Olomouc, Czechoslovakia, assignor to Kartarik, Incorporated, St. Paul, Minn., a corporation of Minnesota

Application December 18, 1946, Serial No. 135,587

Term of patent 14 years

(Cl. D34—15)

To all whom it may concern:

Be it known that I, Rudolph Kartarik, a citizen of Czechoslovakia, residing at Olomouc, Czechoslovakia, have invented a new, original, and ornamental Design for a Tricycle, of which the following is a specification, reference being had to the accompanying drawing, forming a part thereof.

In the drawing:

Figure 1 is a perspective view of a tricycle, showing my new design;

Fig. 2 is a plan view of the same, and

Fig. 3 is a front elevational view of the same.

I claim:

The ornamental design for a tricycle, as shown.

RUDOLPH KARTARIK.
